DETERGENT CONTAINING β,β' -DECYLAminOBIS-ETHANOLPROPIONAMIDE

Lloyd F. Henderson, Fair Lawn, and Charles H. Schramm, Hillsdale, N. J., assignors to Lever Brothers Company, New York, N. Y., a corporation of Maine

No Drawing. Application August 10, 1955
Serial No. 527,635

13 Claims. (Cl. 252—153)

This invention relates to light duty detergent compositions which can be formulated either as liquid solutions or as powders and which contain a small amount of β,β' -decylaminobis-ethanolpropionamide to improve the sudsing and detergency of the compositions.

There are two general types of detergent compositions available on the market: light duty and heavy duty detergents. Heavy duty detergents have the ability to remove stubborn soil and prevent soil redeposition in laundering. These are all-purpose detergents, usually available in powdered form, and contain polyphosphates as builders. However, these detergents by virtue of their polyphosphate content and their strong detergency tend to irritate sensitive skin and therefore are less favored by the housewife for dishwashing and fine laundering. To compete with soap for these purposes, light duty detergents have been formulated. These lack the polyphosphate builders but have a detergency which is adequate for dishwashing and light laundering, and are not as hard on the skin.

Many light duty detergents have been made available in liquid form, as solutions of synthetic detergents containing a high concentration of the active detergent. Such detergents possess special properties, and are quite attractive to the housewife because there is no need to dissolve the detergent. A washing solution is obtainable simply upon dilution of an easily measured portion of the concentrated liquid with water. However, liquid detergents present a special problem. They should be highly concentrated, and yet not become cloudy or precipitate solids even at low temperatures, i. e., 45° F. or below, which may be encountered in storage, to avoid a deterioration in performance due to separation of active ingredients. A cloudy or two-phase solution containing precipitated solids has little sales appeal on the store shelf. This requirement complicates the obtention of a highly concentrated detergent solution, and makes it difficult to formulate a liquid detergent which is competitive with a dry powdered product, for the latter need not meet special solubility requirements inasmuch as it is customarily used in dilute solutions.

It is imperative that the liquid detergent solution be highly concentrated in order to keep at a minimum the volume of solvent in the concentrate, to make it possible to use small measured portions for each wash. From a marketing standpoint the concentration of the liquid detergent should be such that the package of liquid detergent is roughly equivalent to a package of dry powdered detergent and is of convenient size. From 12 to 16 ounces of liquid detergent should be approximately equal in use properties to a 19 to 20 ounce package of the equivalent dry powdered light duty detergent.

An important feature of the light duty detergent is its sudsing power. Most housewives who wash dishes by hand still rely upon the sudsing of the washing solution to tell them when the detergency has been exhausted. The standardized dishwashing tests are based upon this principle, and the end point of the test is the time when

2

the suds no longer completely cover the surface of the washing solution. As is well known, most synthetic detergents are deficient in sudsing power, and this difficulty is usually overcome by incorporating an ingredient which enhances suds. For use in liquid detergents, however, it is essential that the added ingredient be soluble in the solution to a sufficient extent to permit the preparation of solutions of high concentrations. The solubility of this agent in the solvents used in liquid detergents thus is an important property of such agents. Many such agents are very sparingly soluble in water.

In accordance with the invention, synthetic detergent compositions are provided which contain β,β' -decylaminobis-ethanolpropionamide and an organic nonsoap detergent. Inasmuch as the detergent compositions of the invention are primarily intended for light duty purposes, these are the only essential components of the composition. However, if the composition is to be in liquid form, a solvent for the synthetic detergent and the β,β' -decylaminobis-ethanolpropionamide will of course be present in an amount to completely dissolve them.

β,β' -Decylaminobis-ethanolpropionamide is a new compound which is not described in the literature:

30 It is prepared by reacting decylamine with methyl acrylate to form methyl β,β' -decylaminodipropionate, which then is reacted with ethanolamine to form β,β' -decylaminobis-ethanolpropionamide. The reaction is shown 35 by the following sequence of reactions:

40 45 50 55 2 mols of the methyl acrylate and 2 mols of the ethanolamine are required.

The reaction with the methyl acrylate is carried out by refluxing the necessary amounts of the starting materials. The reaction with the ethanolamine is carried out by simply mixing, followed by heating on a steam bath until reaction is complete, which will require about 24 hours. The following illustrates the procedure.

EXAMPLE A

One hundred fifty-seven grams of decylamine were refluxed with 344 grams of methyl acrylate for 20 hours. The excess acrylate was removed by distillation. The yield of crude methyl β,β' -decylaminobispropionate was quantitative and the material was of sufficient purity for use in the next step.

60 65 250 grams of the methyl β,β' -decylaminopropionate thus obtained was reacted with 120 grams of ethanolamine at 85 to 90° C. for 12 hours. A quantitative yield of the β,β' -decylaminobis-ethanolpropionamide was obtained.

This material can be combined with any synthetic detergent to give a light duty detergent composition. Anionic, nonionic and cationic synthetic detergents and mixtures thereof can be used. The alkyl aryl sulfonates and the alkyl sulfates are especially preferred.

Enough of the β,β' -decylaminobis-ethanolpropionamide would be used to enhance sudsing and/or detergency of the synthetic detergent in aqueous solutions of washing concentrations. Usually from 2% to 10% is adequate.

The alkyl aryl sulfonates are a class of anionic synthetic detergents well known in the art under this name. They have the general structure

wherein R is a straight or branched chain hydrocarbon radical having from 1 to about 24 carbon atoms, at least one R having 8 to 24 carbon atoms, x is a number from 1 to 5, and may be an average number, and M is hydrogen, an alkali metal or an organic amine cation. R can for example be methyl, ethyl, hexyl, isohexyl, octyl, tert-octyl, isoctyl, decyl, dodecyl, or octadecyl.

One example thereof are the sulfonated polypropylene benzene alkanes, having an alkyl radical characterized by the branched chain structure of polypropylene and attached by a tertiary alkyl carbon to the benzene ring, and having the following general structure:

where M is hydrogen, an alkali metal or an organic amine cation, and R₁ and R₂ are alkyl, of the type formula C_nH_{2n+1} , and at least one R is a straight or branched chain polypropylene group, the whole alkyl group containing preferably twelve to fifteen carbon atoms. These are known compounds, whose preparation and properties are set forth in U. S. Patent No. 2,477,383 to Lewis, issued July 26, 1949; they are available in commerce under the trade names "Oronite," "Ultrawet" and "Neolene."

Another example thereof are the alkyl aryl sulfonates made by chlorinating a ketyl hydrocarbon, and condensing this with benzene, followed by sulfonating. These are the "Nacconols."

The alkyl sulfates are characterized by the structure RSO₄M, where M is hydrogen or an alkali metal, i. e., ammonium, sodium, or potassium, or an organic amine cation, and R is a straight or branched chain saturated or unsaturated hydrocarbon radical, such as myristyl, palmityl, oleic, stearyl, and lauryl, as well as the mixed alkyl radicals derived from fatty oils, such as coconut oil fatty alkyl, tallow fatty alkyl, cottonseed oil fatty alkyl and fish oil fatty alkyl radicals. R usually has from eight to eighteen carbon atoms, preferably from twelve to sixteen carbon atoms.

Another class of anionic synthetic detergents are the sulfated oxyethylated alkyl phenols, which have the following general formula:

wherein R is a straight or branched chain saturated or unsaturated hydrocarbon group having at least eight carbon atoms up to approximately eighteen carbon atoms, A is oxygen, sulfur, a carbonamide or thiocarbonamide group or a carboxylic or thiocarboxylic ester group, x is a number from three to eight, and M is hydrogen or an alkali metal, e. g., sodium, potassium, and ammonium, or an organic amine cation. R can, for example, be a

straight or branched chain octyl, nonyl, decyl, dodecyl, tetradecyl or octadecyl group. When the ammonium or organic amine salts are used, somewhat higher concentrations of detergent can usually be incorporated in aqueous solution.

In addition to these there may be mentioned sulfonated castor oil, esters and ethers of isethionic acid, 1,2, dihydroxy propane-3-sulfonic acid, sulfates of oxyethylated alcohols and sulfuric acid esters of monoglyceride and glycerol monoethers. The salts of these acids are usually employed.

Another class of useful anionic synthetic detergents are the amidoalkane sulfonates which are characterized by the following structure:

where M is hydrogen or an alkali metal, i. e., ammonium, sodium, or potassium, or an organic amine cation, n is a small whole number from one to about five, preferably two or three, R' is hydrogen, or an alkyl, aryl, or cycloaliphatic group, such as methyl, and R is an alkyl or alkylene radical, such as myristyl, palmityl, oleyl and stearyl. Sodium palmitic tauride, sodium palmitic methyl tauride, sodium myristic methyl tauride, sodium palmitic stearic methyl tauride and sodium palmitic methyl amido-propane sulfonate have been found to be particularly suitable for use in the compositions of the invention.

The anionic synthetic detergents can be used in the form of the free acid, which can be neutralized in situ in the liquid detergent solution by addition of an organic amine or ammonium hydroxide. They are also readily available as the alkali metal salts, such as sodium, potassium and ammonium, and these would generally be used. However, the ammonium or organic amine salts may be more soluble, and in this event would be preferred, particularly from the standpoint of increasing the detergent concentration to a maximum. The amine can be any of those listed hereinafter.

There may also be used, either alone or in admixture with the anionics, nonionic synthetic detergents such as polyoxyalkylene ethers, which retain the terminal OH groups, as the glycols, and in which the terminal OH groups are substituted, as the mono and diethers thereof, such as the polyoxyalkylene alkyl phenols, polyoxyalkylene fatty acid amides, and alkyl polyoxyalkylene oxy- and thioether and oxy- and thioester nonionic detergents.

Many polyoxyalkylene glycol ether synthetic detergents have the following general formula:

where R is a straight or branched chain saturated or unsaturated hydrocarbon group having from eight to eighteen carbon atoms or an aralkyl group having a straight or branched saturated or unsaturated hydrocarbon group of from eight to eighteen carbon atoms attached to the aryl nucleus, and attached to A through the aryl nucleus, A is selected from the group consisting of ethereal oxygen and sulfur, carboxylic ester and thiocarboxylic ester groups, R' and R'' are hydrogen or methyl, and x is a number from eight to twenty. R can for example be a straight or branched chain octyl, nonyl, decyl, octadecyl, dodecyl, tetradecyl, or hexadecyl group, or an alkyl aryl group such as octylbenzene, nonylbenzene, decylbenzene, octadecylbenzene, etc.

When R is alkyl it will be evident that the synthetic detergent can be regarded as derived from an alcohol, mercaptan, oxy or thio fatty acid of high molecular weight, by condensation with ethylene oxide, 2,3-butylene oxide or 1,2-propylene oxide. Typical of this type of alkyl ether are the condensation products of oleyl or dodecyl alcohol or mercaptan with from eight to seven-

teen moles of ethylene oxide, such as "Emulfor ON," "Nomic 218" and "Sterox SE" and "SK." Typical alkyl esters are "G1226" and "Rex" (polyoxyethylene ester of tall oil acids), "Sterox CD," "Neutronyx 330" and "331" (higher fatty acid esters of polyethylene glycol).

When R is aralkyl, the synthetic detergents can be derived from an alkyl phenol or thiophenol.

The polyoxyalkylene alkyl phenols and thiophenols have the following general formula:

where R is a straight or branched saturated or unsaturated hydrocarbon group having at least eight carbon atoms up to approximately eighteen carbon atoms, R' and R'' are hydrogen or methyl, A is oxygen or sulfur and x is a number from eight to twenty. R can, for example, be straight or branched chain octyl, nonyl, decyl, dodecyl, tetradecyl, hexadecyl or octadecyl. Typical are the condensation products of octyl and nonyl phenol with from eight to seventeen moles of ethylene oxide, available commercially under the trade names "Oronite NIW," "Antarox A-400," "Igepal CA" and "CO," "Triton X-100," "Neutronyx 600" and "Tergitol NPX."

Another class of nonionic synthetic detergents are the "Pluronics," which have the structure:

m and *m'* represent the average number of oxyethylene units, and *n* the average number of oxypropylene units. See U. S. Patent No. 2,674,619. The sum of *m* and *m'* preferably is within the range from 15 to 41, and *n* preferably is within the range from 17 to 31.

For light duty purposes, the detergent composition need not contain supplemental builders. Because of solubility problems, they will usually not be incorporated in liquid detergent solutions. However, these can be added if desired to the powders for special purposes such as for use in certain waters. Typical of such additives are alkali metal and alkaline earth metal sulfates, chlorides, silicates, borates, carbonates, metaphosphates, and orthophosphates, such as sodium silicate, magnesium sulfate, sodium tetraborate, sodium carbonate, sodium sulfate, trisodium phosphate, potassium carbonate, disodium orthophosphate, sodium metaphosphate, calcium sulfate, calcium chloride, sodium chloride, sodium borate and potassium metaphosphate.

In addition to or instead of the above-mentioned supplemental inorganic salts, organic materials such as starch, polyethylene glycols, polyvinyl alcohols, ethylhydroxyethyl cellulose, and salts of carboxymethylcellulose and cellulose sulfuric acid esters can be used as builders. It has been found that between about 0.1 and 1% of such materials is useful.

The builder mixture is so chosen that the composition obtained in an aqueous 0.14% solution has a pH of 6 or above. Preferably, its pH lies within the range from 6 to about 10 since solutions which are more alkaline may be irritating to the skin and tend to weaken some fabrics, particularly woolens.

The powdered detergent composition is prepared by conventional methods, as by blending the ingredients thereof in an aqueous solution or slurry and then drying the resulting mixture in a spray or drum dryer at elevated temperatures. The β,β' -decylaminobis-ethanolpropionamide may be added to the detergent composition at any stage of its manufacture, or to the finished powder.

In the case of liquid detergents the ingredients may be dissolved in warm water, or water-and-alcohol, or alcohol; they may be dissolved separately in alcohol or water and then these solutions are mixed. Thereafter, the solution may be diluted to the desired concentration. The amount of solvent should be sufficient to dissolve all of the solid components, and furnish a detergent solution which does not cloud or form a precipitate at temperatures as low as 45° F. The amount of total solids in the composition is variable and is limited only by the solubility of the components in the solvent. Usually, it is desirable to have the synthetic detergent concentration as high as possible, and inasmuch as the β,β' -decylaminobis-ethanolpropionamide improves the detergency and sudsing power of the syndet, as much of this as is feasible will also be present. For optimum effects, the amount of total solids should be within the range from about 20% to about 55%, depending upon solubility. Of this, the synthetic detergent should range from about 15% to about 50% and the concentration of the β,β' -decylaminobis-ethanolpropionamide should be within the range from about 2% to about 10%.

Water is the preferred solvent. When the solid synthetic detergent and β,β' -decylaminobis-ethanolpropionamide are not sufficiently soluble in water alone, their solubility may be improved by the use of a mixture of water and a water-miscible lower aliphatic alcohol, such as ethyl or methyl alcohol, water-miscible glycols, such as ethylene glycol and diethylene glycol, as well as the alkylamines. The latter solvents also make it possible to control the pH, which usually should be within the range from about 6 to about 10 for optimum detergency. pH control also can be obtained by incorporating an inorganic base, such as sodium, potassium or ammonium hydroxide, in the liquid detergent, as well as organic amines, such as methylamine, butylamine, hexylamine, and the like. The amount of the base is not critical, but it is desirable to have sufficient base present to neutralize all free acids, including detergent acids and any free inorganic acid contaminants therewith, plus an excess amount to buffer acids encountered in washing and maintain a reserve of alkalinity in the wash solution. In addition to this, of course, the amine may have solvent properties and be relied upon in part for this function.

Exemplifying the amines useful for these purposes, as well as for preparing salts of the anionic synthetic detergents supra, are water-soluble, strongly basic amines such as triethanolamine, diethanolamine, monoethanolamine, ethylenediamine, diethylenetriamine, tetraethanol ammonium hydroxide, morpholine, mixed isopropanolamines, monoisopropanolamine, diethylene glycol amine, and amino ethyl ethanolamine. The alkylamines, either mono-, di- or tri-, are preferred.

It may be noted that lower alcohols such as ethyl alcohol and polyethylene glycols of low molecular weight may reduce the viscosity of the solution when used in small amounts. On the other hand, polyethylene glycols of higher molecular weight may tend to increase viscosity even when employed in small amounts. Polyethylene glycols having a molecular weight within the range from 150 to 6000 are preferred, but as indicated the chain length is not critical; those having lower molecular weights can be used, for example, diethylene glycol and triethylene glycol.

The composition may also contain dyestuffs and perfumes to suit the housewife's desire. It is customary to mask the odor of organic amines, and those skilled in the art are aware of perfumes which meet this need.

The following examples illustrate the invention.

Examples 1 to 10

Ten detergent compositions were prepared having the following composition:

Example No.	Percent by weight											
	Control A	Control B	1	2	3	4	5	Control C	6	7	8	9
β, β' - Decylaminobis - ethanolpropionamide	100	100	52.6	35.7	27.1	21.8	10	52.6	35.7	27.1	21.8	10
Ammonium Alkyl Aryl Sulfonate ¹		47.4	64.3	72.9	78.2	90		47.4	64.3	72.9	78.2	90
Stepanol WAT ²												

¹ 27.4% active, alkyl having from 12 to 16 carbon atoms.
² Lauryl sulfate, technical, 38.5% active, triethanolamine salt.

Each of the compositions was dissolved in 300 p. p. m. water and subjected to a standard dishwashing test at 25° F. The compositions were compared with three control compositions containing the β, β' -decylaminobis-ethanolpropionamide and each of the synthetic detergents alone. Six-quart quantities of the solution were used in 30° F. each test.

The dishwashing test determined the number of artificially soiled dinner plates washed under standardized conditions. The apparatus used was a Hobart mixer, model C-210. The dinner plates were circular, nine inches in diameter. About 5 to 5.5 grams of standard dishwashing soil was spread evenly over the top of each plate with a spatula. This soil was composed of 9 parts weight of Covo, emulsifier free, added to 8 parts by weight of Pillsbury's bread flour and 1.25 ml. of green coloring for each pound of flour used, all thoroughly mixed.

The test solution was brought to a temperature of 116° F. The plates were then washed by hand, using freshly laundered dish cloths. Washing was continued until the suds in the pan of solution no longer completely covered the surface of the water.

The dishwashing capacity of the detergent is reported in the table as the number of plates washed up to the time the end point is reached:

Example No.	Average Plates Washed	Total Grams Active	Example No.	Average Plates Washed	Total Grams Active
Control A...	5	4.467	Control A...	5	4.467
	4	3.350		4	3.350
	2	1.117		2	1.117
	0	0.558		0	0.558
	31	4.000		33	4.000
	25	3.000		26	3.000
Control B...	10	1.000	Control C...	8	1.000
	3	0.500		4	0.500
	51	4.234		48	4.234
	42	3.175		37	3.175
	14	1.058		16	1.058

5...					

The dishwashing test results show that the combination of the β, β' -decylaminobis-ethanolpropionamide and the synthetic detergent increases by approximately 50% the total number of plates which can be washed by each component alone at the same concentration, demonstrating the improved effect obtained from the combination.

Example 11

This is an example of a highly concentrated liquid detergent:

Percent
Phenyl polypropylene sodium sulfonate (alkyl of 12 to 15 carbon polypropylene)----- 20.0
Antaron K-460 A (ammonium salt of sulfated ethoxynated nonyl phenol, prepared from condensation of nonyl phenol with five moles of ethylene oxide) (57% active)----- 15.0
β, β' -Decylaminobis-ethanolpropionamide ----- 6.6
Ethyl alcohol ----- 20.0
Water, perfume, etc. ----- 38.4

This composition remains clear at temperatures as low as 45° F. and has a pH of 6.7.

This formulation has excellent detergency and is especially suited for dishwashing purposes.

Example 12

55 The following is an additional example of a highly concentrated formulation:

Percent
Sodium ketyl benzene sulfonate (alkyl averaging fourteen carbon atoms, from kerosene fraction hydrocarbons)----- 25.0
Antaron K-460A ----- 15.0
β, β' -Decylaminobis-ethanolpropionamide ----- 3.0
Ethyl alcohol ----- 20.0
Water, perfume, etc. ----- 37.0

65 This composition has a pH of 7.2 and remains clear and uniform without separation of solid materials at temperatures as low as 35° F. The composition has excellent detergency, and is particularly suitable for dishwashing.

Examples 13 to 19

70 Seven detergent compositions were prepared having the following formulations:

	Examples						
	13	14	15	16	17	18	19
Ammonium phenyl polypropylene sulfonate (alkyl of 12 to 15 carbon polypropylene) percent	35	0	22	22	35	0	0
Ammonium salt of sulfated ethoxynated nonyl phenol (five moles ethylene oxide) percent	0	35	13	13	0	35	0
β,β' -Decylaminobis-ethanolpropionamide percent	9	9	9	3	0	0	35
Ethyl alcohol do	15	15	15	15	15	15	15
Water, perfume, etc. do	41	41	41	47	50	50	50
Remains clear as low as ° F	86	-10	14	4	34	-10	87
Solution pH	7.25	7.2	7.2	7.2	7.23	7.23	

Each of the compositions was subjected to the standardized dishwashing test of Examples 1 to 10.

The results of the dishwashing tests were as follows:

Example No.	NUMBER OF PLATES WASHED IN 6 QTS. WATER AT 116° F			
	50 p. p. m.		180 p. p. m.	
	4 g.	3 g.	4 g.	8 g.
13	26	23	29	49
14	22	16	25	44
15	32	22	33	59
16	27	20	29	48
17	10	7	14	26
18	15	12	20	33
19	None	None	None	None

The compositions were subjected to standardized washing tests in the Terg-O-Tometer, using 1250 cc. each of washing solutions in 180 p. p. m. water prepared by dissolving the amount of detergent indicated in the table in 17 gallons of water. Each wash was carried out at 120° F. and 90 R. P. M. for 20 minutes. Eight soiled cotton swatches (vacuum cleaner dirt) and four unsoiled swatches were present in each wash. The detergency was determined by examination of the soiled cotton swatches after the washing and the redeposition by examination of the unsoiled swatches after the washing. The average reflectometer reading of the soiled cloth after washing minus 30 is reported as detergent units and the average reflectance reading of the unsoiled cloths after washing is reported as redeposition units. For comparison purposes, typical results for a commercial polyphosphate-built alkyl aryl sulfonate detergent are included in the table:

Example No.	Detergency Units		Redeposition Units	
	3 oz.	6 oz.	3 oz.	6 oz.
	17.8	22.3	73.6	78.0
13	26.7	27.1	77.9	77.6
14	25.9	26.7	78.9	79.5
15	26.7	27.4	79.3	79.6
16	19.4	25.1	75.8	78.8
17	25.5	26.5	76.1	75.8
18	20.2	19.6	65.3	72.0
19				
Commercial polyphosphate built alkyl aryl sulfonate detergent (20% Sodium Oronite, 47% mixed pentasodium tripolyphosphate and tetrasodium pyrophosphate)	27.5	30.8	78.6	78.9

Example 20

The following is an example of a medium-concentration light duty detergent:

25	Phenyl polypropylene sulfonic acids, ammonium salt (alkyl of 12 to 15 carbon polypropylene) --	Percent
	Ammonium salt of sulfated ethoxynated nonyl phenol, condensed with five moles of ethylene oxide --	16.63
30	β,β' -Decylaminobis-ethanolpropionamide --	10.43
	Ethyl alcohol --	7.00
	Perfume --	20.00
	Water, etc. --	0.2
35	This formulation remains clear at temperatures as low as 29° F. and has a pH of 6.8.	45.74

All parts and percentages in the specification and claims are by weight, and when with reference to components of the detergent solution are based on the weight of the solution unless otherwise indicated.

40 We claim:

1. A light duty detergent composition consisting essentially of a synthetic organic nonsoap detergent selected from the group consisting of anionic and nonionic synthetic organic nonsoap detergents and an amount 45 within the range from about 2 to about 10% by weight of the synthetic nonsoap detergent of β,β' -decylaminobis-ethanolpropionamide to enhance the detergency and sudsing of the synthetic nonsoap detergent.

2. A light duty detergent composition in accordance 50 with claim 1 in which the synthetic nonsoap detergent is an anionic synthetic nonsoap detergent.

3. A light duty detergent composition in accordance 55 with claim 2 in which the anionic synthetic nonsoap detergent is an alkyl aryl sulfonate.

4. A light duty detergent composition in accordance 60 with claim 2 in which the anionic synthetic nonsoap detergent is an alkyl sulfate.

5. A light duty detergent composition in accordance 65 with claim 2 in which the anionic synthetic nonsoap detergent is in the form of the organic amine salt.

6. A light duty detergent composition in accordance 70 with claim 2 in which the anionic synthetic nonsoap detergent is in the form of the sodium salt.

7. A light duty detergent composition in accordance 75 with claim 2 in which the anionic synthetic nonsoap detergent is in the form of the ammonium salt.

8. A light duty detergent composition in accordance 80 with claim 2 in which the synthetic nonsoap detergent is a nonionic syndet.

9. A light duty detergent composition in accordance 85 with claim 8 in which the nonionic synthetic nonsoap detergent is a detergent polyoxyalkylene ether.

10. A light duty detergent composition in accordance 90 with claim 8 in which the nonionic synthetic nonsoap detergent is a polyoxyalkylene ether glycol.

11

11. A light duty detergent composition in accordance with claim 8 in which the nonionic synthetic nonsoap detergent is a polyoxyalkylene alkyl phenol.

12. A concentrated light duty liquid detergent composition which remains clear and uniform without separation of solid materials at low temperatures consisting essentially of an aqueous solution of synthetic organic nonsoap detergent selected from the group consisting of anionic and nonionic synthetic organic nonsoap detergents in an amount within the range from about 15% to about 50% to impart detergency to the solution and β,β' -decyl-amino-bis-ethanolpropionamide in an amount within the range from about 2 to about 10% by weight of the syn-

12

thetic nonsoap detergent to enhance the sudsing and detergency of the synthetic nonsoap detergent.

13. A concentrated light duty liquid detergent composition in accordance with claim 12 which contains 5 ethyl alcohol.
